LIGHTING FIXTURE

Filed April 14, 1930

UNITED STATES PATENT OFFICE

GEORGE H. COLE, OF MILWAUKEE, WISCONSIN, ASSIGNOR TO LINE MATERIAL COMPANY,
OF MILWAUKEE, WISCONSIN, A CORPORATION OF DELAWARE

LIGHTING FIXTURE

Application filed April 14, 1930. Serial No. 444,182.

This invention relates to certain new and useful improvements in street lighting fixtures and refers more particularly to means for mounting glassware to ornamental standards or posts.

In street lighting fixtures of this type, a glass bowl, usually of ornamental configuration, surrounds the lamp to diffuse its light, and heretofore it has been customary to attach such glassware to a supporting member at the top of the post or standard by means of screws or other similar means which directly engaged the lower periphery of the bowl. This method of mounting the glassware has been objectionable for the reason that attaching means located only at the bottom of the bowl caused considerable strain to be imposed on the glassware during strong winds. This direct application of unyielding mechanical pressure produced by tightening the attaching screws also very often cracked the bowls.

Means were therefore devised whereby the glassware was rigidly held not only at its bottom, but also at a medial point, but existing devices for this purpose are costly and have proved objectionable in that a considerable shadow was cast by the external supporting structure. It is, therefore, an object of this invention to provide means for mounting glassware of the character described which is entirely concealed and provides a firm but yielding means of attachment.

Another object of this invention resides in the provision of means for anchoring glassware of the character described to its supporting structure, which is applied to the glassware at a point spaced considerably from the support to increase the stability of the glassware.

A more specific object of this invention resides in the provision of spring means for anchoring glassware of the character described to its supporting structure which is adapted to be concealed within the glassware to provide a resilient but firm means of attachment.

And a further object of this invention resides in the provision of an anchoring means

for glassware of the character described which places the entire bowl in compression.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a side elevational view of a lighting fixture embodying my invention, parts thereof being broken away to illustrate structural details; and

Figure 2 is a detail sectional view taken through Figure 1 on the plane of the line 2—2.

Referring now more particularly to the accompanying drawings, the numeral 5 represents the top of a street lighting standard or post which is known in the art as a capital and which forms the direct support for the fixture, indicated generally by the numeral 6. The fixture 6 may be of any desired design and comprises a socket receptacle 7 supported from the capital 5 to receive a conventional socket 8 having a bulb 9 mounted therein.

The bulb and its supporting structure is enclosed in a bowl 10 formed of glass and usually of ornamental design. The lower end of the bowl rests on a rubber or other yieldable gasket 11 forming the bottom of an annular channel 12 which may be part of the capital or may be formed in an adaptor ring 13 secured to the top of the capital.

A plurality of contractile springs 14 having their opposite ends hooked over the top peripheral edge 15 of the bowl 10 and in apertures 16 formed in lugs 17 projected inwardly from the adaptor ring 13, hold the

bowl in position. By attaching the springs to the upper portion of the bowl, maximum stability is obtained and the bowl is held in compression at all times.

The open top of the bowl is preferably closed by a separate hood or dome section 18 which may be formed of glass to complete the design of the fixture. An ornamental metal ring 19 serves to connect the dome 18 with the bowl 10, the upper marginal edge 5 of the ring being directed inwardly, as at 20, to overlie the outwardly directed peripheral edge 21 of the dome 18, and a yieldable gasket 22 being preferably provided between the flange 20 and the outwardly directed 10 portion 21.

The peripheral edge portion 21 of the dome telescopes over the adjacent edge of the bowl 10 and rests on the hooks of the 20 springs 14, but if desired, the top marginal edge of the bowl 10 may be notched at intervals about its periphery for a depth sufficient to receive the hooks of the springs and allow the dome to rest directly on the 25 top edge of the bowl. Screws 23 threaded in the ring 19 at intervals about its circumference engage in an annular channel 24 formed at the top of the bowl 10 to maintain the ring 19 and the dome 18 rigidly connected with the bowl.

From the foregoing description taken in connection with the accompanying drawings, it will be readily apparent to those skilled in the art to which an invention of the character described appertains, that I provide a 35 novel inexpensive means for anchoring glassware of street lighting fixtures to their supporting structures, which greatly increases the stability of the mounting and provides a positive and firm attachment 40 without imposing direct mechanical strains on the bowl and wherein the anchoring means is entirely concealed.

What I claim as my invention is:

- 45 1. In a lighting fixture of the character described comprising a support, a two part glass bowl mounted on said support, resilient means engaging one part of said bowl between said parts to resiliently urge said bowl onto said support, said other part being superimposed on the first part and on said means, and joined to said first part through an ornamental metal ring, substantially as described.
- 50 2. In an ornamental lighting fixture of the character described, a support, a two part glass bowl supported from said support and permitting access to the lighting fixture by removal of one of said parts, resilient means engaging one part of said bowl between said sections and at spaced 55 points about the periphery thereof to resiliently urge said last named part of said bowl onto said support, means removably retaining said other section in juxtaposition

with said first section, substantially as described.

3. In a lighting fixture of the character described comprising a support, a two part glass bowl mounted on said support, said bowl comprising an upper and a lower section, resilient means engaging one of said sections on the edge adjacent said other section to resiliently urge said bowl onto said support, said other section being superimposed on said first section and on said means, a metal ring having a flange engaging said last named section and means engaged with said ring and with means on said first named section to hold the two sections in juxtaposition.

4. In a lighting fixture of the character described, comprising a support, a two part glass bowl mounted on said support, said bowl comprising an upper section and a lower section resilient means engageable with the upper edge of the lower section and engageable with said support for constantly urging said lower section onto said support, an annular outstanding flange on said upper section forming a seat for said bowl on said resilient means, a metal band having an inturned annular flange seated on the upper side of said outturned annular flange and means on said band cooperating with means on the lower section of said bowl to hold the two sections of said bowl in juxtaposition.

In testimony whereof I have hereunto affixed my signature.

GEORGE H. COLE.
